UNITED STATES PATENT OFFICE.

GEORGE BOLD, OF PLAINFIELD, NEW JERSEY.

AIR-SHIP.

No. 853,760.

Specification of Letters Patent.

Patented May 14, 1907.

Application filed November 27, 1906. Serial No. 345,280.

To all whom it may concern:

Be it known that I, GEORGE BOLD, a citizen of the United States, and a resident of Plainfield, in the county of Union and State of New Jersey, have invented a new and Improved Air-Ship, of which the following is a full, clear, and exact description.

This invention is an improvement in air-ships, having among other objects to provide for the utilization of side currents of air when the ship is in flight, by employing the same to assist in driving the ship and also to provide for the easy control of the ship's movements by in effect giving flexibility to its hull and for the convenient storage and discharge of ballast.

Reference is to be had to the accompanying drawings forming a part of this specification, in which similar characters of reference indicate corresponding parts in all the figures.

Figure 1 is a side elevation of the ship complete; Fig. 2 is a front end elevation of the same; Fig. 3 is a horizontal section substantially on the line 3—3 of Fig. 1 looking in the direction of the arrows; Fig. 4 is a longitudinal, central, vertical section through the ship body and a fragment of one of the gas-bags; Fig. 5 is a section on the line 5—5 of Fig. 3, looking in the direction of the arrow; Fig. 6 is a cross section on the line 6—6 of Fig. 5, and Fig. 7 is a rear end view of the rudder.

In carrying out my invention I employ a car or hull 1, which is substantially semi-elliptical in cross section with the sides converging toward flattened ends 2, as shown in dotted outline in Fig. 3. The bottom of the hull 1, as shown in Fig. 2, is constructed with a concave portion 3 running the length of the hull, forming at each side projecting angles 4, which give the ship a firm seating when resting on the ground. Just above the concave portion 3 in the hull of the ship is a lower or main deck 5, which is supported by a series of cross partitions 6 forming in connection with said hull, a series of ballast compartments. Each of these compartments is provided with an opening 7 passing through the bottom of the ship, over which is seated a valve 8 normally forced to its seat by a spring 9 interposed between the upper face of the valve and a crossbar 10. The upper end of each valve stem is connected by a cord or other device 11 having a suit-

able operating handle 12 arranged above the main deck 5.

The ballast compartments may be filled with water, sand or other flowing heavy medium, which may be discharged through any one of the openings 7, by withdrawing its respective valve from its seat by the attached handle above the main deck. It is obvious from this construction that the ship may be lightened uniformly throughout its length, or one end lightened only, adapting the angular position of the ship to be controlled while in flight.

Carried above the hull 1 on suitable supports 13 is a marginal upper deck 14, which is made accessible to and from the lower deck by a connecting ladder 15. The upper deck 14 supports at each end a frame-work 16, preferably constructed of light tubing bent or otherwise formed into rectangular shape. 75 These rectangular frames support at suitable intervals, three being shown in Fig. 2, bands 17, each having a net-work 18 arranged at its outer side. In the alining bands of each frame gas-bags 19 are placed, which are held 80 from longitudinal movement by the nets 18 and are further supported intermediate their length by bands 17^a connected to the frames 16 by longitudinal bars 20. This construction provides for the secure holding 85 of the gas-bags, positively maintaining the same from movement in any direction, as shown in Figs. 1 and 2. At each side of the frame 16 are attached masts 21, also constructed of tubing and carrying sails 22 controlled in the usual or any preferred manner from the upper marginal deck 14. These sails and also the gas-bags may, under some conditions, be dispensed with, as for example, should the power means hereinafter 95 described and carried by the hull of the ship, be found sufficient.

At the forward end of the ship is arranged a pointed, hollow body 23, which is preferably of pyramidal shape, and is pivoted to the forward end 2 on a pin 24, adapting the body to be moved side from side in directing the movement of the ship laterally. A second pivotal joint at right angles to the pin 24 is formed by a pin 25 adapting the body 23 to 105 be moved in a vertical plane and controlling the movement of the ship in this direction. The pivots formed by the pins 24 and 25, in effect, form a universal joint which may be of such stiffness as to hold the body 23 in any 110

position in which it is set. For controlling the movement of the body 23, a handle 26 is rigidly attached thereto and passes to a point within the ship where it may be readily operated from the deck 5.

Journaled at each side of the hull 1 of the ship in a bearing-box 27, is a hollow spindle 28, as best shown in Fig. 5, and held from longitudinal movement by a collar 29 formed as an integral part thereof at the outside of the hull and by a crank arm 30 adjustably fixed to its opposite inner end by a set-screw 31. That part of the spindle extending beyond the collar 29 forms a bearing for the hub of a wind-wheel 32, said hub being slightly counterbored at the outer end for receiving the head 33 of a rod 34. The rod 34 passes through the bore of the spindle 28 and is adapted to clamp the hub of the wind-wheel against the collar 29 by means of a nut 32^a threaded on its outer end and seated on a conical washer 33^a let into a corresponding recess in the shaft 28. By this construction the wind-wheel and shaft may be frictionally connected together or the nut 32^a loosened to permit the wind-wheel to freely turn upon the outer end of the shaft; or if it is desired to hold both the shaft and wind-wheel rigid, a set-screw 35 threaded through the box 27 and contacting with a binding-strip 36 may be screwed up to bind the shaft in its bearing and hold it against rotation.

To each crank arm 30 is pivotally connected a link 37, the opposite end of which is pivoted to a rocker arm 38, the latter being adjustably fixed to a shaft 39 passing through and also journaled in the side of the ship. As shown in Fig. 4, the pivot-bolt or pin at each end of the link 37 is adjustable to change the throw of the crank arms and rocker arms, or to shorten or lengthen the link. To the outer end of each shaft 39 is fixed a rearwardly-extending wing 40, preferably of the shape shown, and having an arm 41 at the opposite side of the shaft 39 which carries a suitable counterweight 42. From the construction and arrangement of the wind-wheels and propellers it is evident that the former will be driven by side currents of air on the ship, causing the propellers to oscillate and assist the ship in its upward flight, or the propellers may be thrown out of action by releasing the rods 34 or by tightening the set-screws 35 as hereinbefore indicated.

At the stern end of the ship is pivoted on a pin or bolt 43 in order that it may be swung from side to side, a hollow body 44 similar in construction to the body 23 but having its outer end slightly truncated, as shown at 45 in Fig. 4, to the outer edge of which is hinged a plate 46 carrying a rudder 47. The shape of the bodies 23 and 44 is such that the resistance of the hull of the ship, when passing through the air, will be reduced to a mini-

mum, whereas their pivotal movement will in effect give great flexibility to the body of the ship as in a bird while in flight adapting the movement of the ship to be easily controlled. The hollow character of the bodies 70 obviously relieves them of unnecessary weight. This rudder, as best shown in Fig. 7, consists of two intersecting blades arranged at right angles to each other, and may be swung to an angular position in a vertical 75 plane by a line 48 leading to a convenient point on the ship. The hollow body 44, and consequently the rudder 47, is moved from side to side on the pivot 43 by lines 49 connected to the outer edges of the body and 80 leading to any desired form of steering mechanism. Fixed on the body 44 to its upper face is a motor 50, having pulleys 51 secured to the outer end of its driving shaft, which are each connected with a pulley 52 through 85 the intermediary of belts 53, one of said belts being crossed in order that the pulleys may be driven in opposite directions. The pulleys 52 are fixed to shafts 54 journaled in the outer ends of arms 55 extending from the 90 body 44. The opposite ends of said shafts 54 carry, respectively, a right and a left hand propeller 56, this construction adapting the propellers to be driven in opposite directions when forcing the ship forward or rearward, 95 thereby steadyng the ship in its flight.

Although I have described the invention in its preferred embodiment, it is evident that the same may be variously modified without departing from the spirit thereof, and I consider myself entitled to such changes as fall within the scope of the annexed claims.

Having thus described my invention I claim as new and desire to secure by Letters Patent:

1. In an air-ship, a hull having a main deck, a series of partitions crosswise arranged between the hull and deck directly connecting them together and forming a series of ballast compartments, and means for discharging ballast from each compartment.

2. In an air-ship, a hull having a main deck, a series of partitions crosswise arranged between the hull and deck directly connecting them together and forming a series of ballast compartments, a valve for discharging ballast from each compartment, and means for independently operating the valves.

3. In an air-ship, a hull having a main deck, a series of partitions crosswise arranged between the hull and deck directly connecting them together and forming a series of compartments, a valve seated over an opening in the bottom of each compartment, and means independently operable above the 125 deck to withdraw each of said valves from their seats.

4. In an air-ship, a hull having a main deck, a series of partitions crosswise arranged between the hull and deck directly connect- 130

- ing them together and forming a series of compartments, a valve seated over an opening in the bottom of each compartment, a spring normally forcing each valve to its seat, and devices connected to said valves and independently operable from said deck to withdraw any one of said valves from its seat.
5. An air-ship having a hull substantially semi-elliptical in cross section with a concave portion in the bottom thereof, for the purpose described.
10. An air-ship having a hull substantially semi-elliptical in cross section and converging toward each end, and a concave portion longitudinally arranged in the bottom of the ship, for the purpose described.
15. An air-ship having a hull with a concave portion running longitudinally in the bottom thereof, for the purpose described.
20. An air-ship having a frame near each end thereof, bands alining with each other secured to the frames, and a gas-bag held in and completely encircled by said bands.
25. An air-ship having a frame at each end thereof, alining bands secured in the frames, means connecting the frames together and supporting an intermediate band, and a gas-bag held in and completely encircled by said bands.
30. An air-ship having a frame at each end thereof, alining bands secured to each frame, an independent net-work at the outer side of each band attached thereto, and a gas-bag carried in the bands and held from longitudinal movement by said net-work.
35. An air-ship having a frame at each end thereof, a series of sets of bands arranged one above the other with the bands of each set alining with each other and carried by the frames, and a gas-bag carried in each set of bands.
40. An air-ship having a series of gas-bags arranged longitudinally thereof and fixedly supported one above the other, and a sail at each side of the gas-bags.
45. An air-ship having a sail near each end and on both sides thereof, and a gas-bag fixed intermediate said sails.
50. In an air-ship, a rectangular frame supported at each end thereof, masts arranged at the outside and supported by each frame, a sail carried by each mast, and a gas-bag supported between the frames.
55. In an air-ship, a rectangular, tubular frame at each end thereof, a tubular mast connected to and at the outside of each frame, a sail carried by each mast, and a series of gas-bags arranged longitudinally of the ship one above the other and supported by said frames.
60. In an air-ship, a rectangular, tubular frame near each end thereof, a tubular mast connected to and at the outside of each frame, a sail carried by each mast, a series of sets of bands supported between the frames, a gas-bag carried by each mast, and a net-work attached to the bands inclosing the outer ends of the gas-bags.
65. An air-ship comprising a hull, a pointed hollow body at the forward end of the hull, and a universal joint connecting the hull and body together, for the purpose described.
70. An air-ship comprising a hull, a hollow pyramid at the forward end of the hull, a universal joint connecting the pyramid and hull together, and means operable within the ship to shift the direction of said pyramid.
75. An air-ship comprising a hull having a main deck, a pointed hollow body arranged at the forward end of the hull, a universal joint connecting the body and hull together, and a lever rigidly attached to said body and operable from said deck for shifting the direction of said body.
80. An air-ship having a wind-wheel journaled at the side thereof, a wing for driving the ship, and means for driving said wing from said wheel.
85. An air-ship having a wind-wheel journaled at the side thereof, a wing for driving the ship, means for driving said wing from said wheel, and means for throwing said wheel out of action.
90. An air-ship having a wind-wheel journaled at the side thereof, a wing journaled at the side of the ship, and means connecting the wheel and wing together adapted to oscillate the wing when the wheel is driven.
95. An air-ship having a wind-wheel journaled at the side thereof, a wing journaled at the side of the ship, a crank-arm adapted to be driven by the wheel, a crank-arm fixed to the wing, and an adjustable link connecting the crank-arms together.
100. An air-ship having a wind-wheel journaled at the side thereof, a wing for driving the ship, counterbalancing means for the wing, and means for driving said wing from said wheel.
105. An air-ship having a wind-wheel journaled at each side thereof, a wing journaled at each side of the ship adapted to oscillate in a vertical plane, and means connecting the wheels with the wings whereby as the wheels are driven the wings may be oscillated.
110. An air-ship having a bearing-box arranged in each side thereof, a hollow spindle journaled in each bearing-box, a wind-wheel journaled on each spindle, means for connecting the wheels with the spindles, a wing journaled at each side of the ship, and means intermediate the wings and spindles whereby they are adapted to be driven therefrom.
115. An air-ship having a bearing-box arranged in each side thereof, a hollow spindle journaled in each bearing-box, a wind-wheel journaled on each spindle, a wing journaled at each side of the ship, means intermediate the wings and spindles whereby they are adapted to be driven therefrom.
120. An air-ship having a bearing-box arranged in each side thereof, a hollow spindle journaled in each bearing-box, a wind-wheel journaled on each spindle, a wing journaled at each side of the ship, means intermediate the wings and spindles whereby they are adapted to be driven therefrom.
125. An air-ship having a bearing-box arranged in each side thereof, a hollow spindle journaled in each bearing-box, a wind-wheel journaled on each spindle, a wing journaled at each side of the ship, means intermediate the wings and spindles whereby they are adapted to be driven therefrom.

- the wings and spindles whereby they are adapted to be driven therefrom, means for clamping the spindles in their boxes, and a rod passing through each spindle adapted to frictionally connect it with said wheels.
28. In an air-ship, a hull, a member pivoted at the stern end of the hull, a propeller carried by said member for driving the ship and a rudder pivoted to said member.
- 10 29. In an air-ship, a hull, a hollow body pivoted to move sidewise at the stern end of the hull, propellers carried by said body, a motor carried by said body for driving the propellers, and means for swinging said body on its pivot from the hull of the ship.
- 15 30. In an air-ship, a hull, a hollow body pivotally connected thereto, propellers carried by the hollow body journaled at opposite sides thereof, a rudder hinged to the rear 20 end of said body, means for moving the hollow body on its pivot, and means for turning the rudder on its hinge adapted to be controlled from the interior of the ship.
- 25 31. In an air-ship, a hull, a body pivoted at the stern end of the hull to swing in a horizontal plane, and a rudder hinged at the rear end of the body to swing in a vertical plane.
32. In an air-ship, a hull, a body pivotally connected to the hull to swing in a horizontal
- plane, and a rudder consisting of two blades 30 intersecting each other at right angles and hingedly connected to the rear end of said body.
33. In an air-ship, a hull, a body pivoted to swing sidewise at the rear end of the hull, a 35 right hand and a left hand propeller journaled at opposite sides of said body, and means for driving said propellers in opposite directions, for the purpose described.
34. In an air-ship, a hull, a hollow body 40 pivoted to swing sidewise at the stern end of the hull, a right hand and a left hand propeller journaled at opposite sides of the body, and a motor carried by said body for driving the propellers in opposite directions.
35. In an air-ship, a hull, a pointed hollow body pivoted to swing sidewise at the stern end of the hull, and a rudder consisting of two intersecting blades hinged at the outer 45 end of said body and adapted to swing in a vertical plane.

In testimony whereof I have signed my name to this specification in the presence of two subscribing witnesses.

GEORGE BOLD.
